[57] CLAIM

The ornamental design for a bulk material handling apparatus, substantially as shown.

DESCRIPTION

FIG. 1 is a front elevational view of a bulk material handling apparatus showing our new design;

FIG. 2 is a view in side elevation thereof;

FIG. 3 is a view in side elevation thereof showing the side opposite that seen in FIG. 2;

FIG. 4 is a view in rear elevation thereof; and

FIG. 5 is a view in top plan thereof.

The bottom view, being substantially devoid of ornamentation, is not shown.

FIG. 3

FIG. 2

FIG. 4

FIG. 5
